DESIGN FOR A DISPLAY BOX FOR HOLDING AN ELECTRIC SHAVER OR SIMILAR ARTI- CLE

Lillian N. Keene, Libertyville, Ill.

Application May 3, 1945, Serial No. 119,379

Term of patent 3½ years

(Cl. D80—5)

To all whom it may concern:

Be it known that I, Lillian N. Keene, a citizen of the United States, residing at Libertyville, in the county of Lake and State of Illinois, have invented a new, original, and ornamental Design for a Display Box for Holding an Electric Shaver or Similar Article, of which the following is a specification, reference being had to the accompanying drawing, forming part thereof.

In the drawing Figure 1 is a perspective view of a display box for holding an electric shaver with the cover closed, showing my new design; Figure 2 is a perspective view of the same with the cover partly raised; Figure 3 is a side elevation of the same; and Figure 4 is an end elevation of the same.

I claim:

The ornamental design for a display box for holding an electric shaver or similar article, substantially as shown.

LILLIAN N. KEENE.
